S. GUBITOSI

SECTIONAL LAST

Filed March 23, 1927

Patented Mar. 27, 1928.

1,664,293

UNITED STATES PATENT OFFICE.

SABINO GUBITOSI, OF BROOKLYN, NEW YORK.

SECTIONAL LAST.

Application filed March 23, 1927. Serial No. 177,483.

This invention relates to lasts as used in the manufacture and repair of shoes whereby a desirable shape is attained and uniformity in size secured, such shoes being 5 made of leather or fabric in a wide variety of styles and heights.

Lasts for this purpose are constructed ordinarily of hard wood in one piece and if the shoes are as closely fitted as they should 10 be, it is a difficult matter to take the last out without injury to it.

In avoiding this difficulty the upper front portion of the last, corresponding to the instep, has at times been made separately 15 removable so that if taken out first the main remaining portion can be raised from the heel and then withdrawn bodily.

A further advance in last making consisted in making the last in two distinct sections, 20 respectively heel and forward portion, the juncture being in an oblique plane extending diagonally from the top at the instep to the bottom at a point just in front of the heel.

25 This type of last is found objectionable because of its weakness in withstanding pressure between the heel and toe portions without slipping; the trouble in keeping the loose parts from becoming mixed and hence 30 unpaired, and if mechanical connections are made between the sections difficulty is found in clamping them in operative position after having been entered into a shoe and in releasing them to permit removal.

35 It is therefore an important object of the present invention to provide an improvement over my Patent, Number 1,596,874, issued August 24, 1926, inasmuch as the 40 number of parts are reduced and the structure materially strengthened.

A further feature resides in the provision of a simple and efficient clamping means by which the sections are held in relation at all times irrespective of their position or in 45 other words the avoidance of all loose and separable parts.

Another advantage is to provide a single key-wrench by which the parts of the last 50 may be firmly clamped together or released to permit of relative sliding movement to allow retraction from the shoe without actual separation, the wrench also being used as an efficient handle grip in taking the last out of the shoe.

55 These objects and aims are effectually accomplished by the novel construction and

arrangement of parts hereinafter fully described and clearly illustrated in the accompanying drawing, constituting an important portion of this disclosure, and in which:— 60

Figure 1 is a longitudinal sectional view showing an embodiment of the invention, the position of the heel portion when raised being indicated in broken lines.

Figure 2 is a transverse sectional view 65 taken on line 2—2 of Figure 1.

Figure 3 is a plan view of the key operated clamp nut.

Figure 4 is a fragmentary sectional view, similar to Figure 1, but showing an alternative form of construction. 70

Figure 5 is a transverse sectional view taken on line 5—5 of Figure 4.

The front or toe section 10 of the last is cut transversely across to produce a 75 smooth bevelled surface 11 at the rear, inclined from the upper instep portion to a point slightly in advance of the heel and neatly joining the complementary surface 12 of the rear or heel section 14 of the last. 80

These sections may be guided laterally by a half round key 15 fixed on the toe section to engage in a corresponding groove 16 formed centrally lengthwise in the surface 11 of the heel section, the groove extending 85 from the bottom of the last to the upper surface.

A cylindrical opening 17 is bored from the top of the forward portion 10, at a point below and parallel with the surface 11, midway between the sides of the last and fixed 90 in this opening is a tube or hollow plug 18 having a cylindrical chamber 19.

Freely slidably in the chamber 19 is a solid round bar 20 in which is fixed near 95 its outer end a stem 21, the same passing outwardly through a slot 22 in the wall of the tube 18 and thence through a corresponding slot 23 in the last material intervening the surface 11 and wall of the bore 100 17, the ends of the slot 23 acting as limit stops for controlling the movement of the bar 20 and stem 21, as seen in Figure 1.

An opening 25 is drilled in the heel portion 14 of the last, at a right angle with its 105 surface 12, through which the stem 21 extends and set in a counterbored recess at the outer end of the opening 25 is a flanged collar 26 to take the thrust of a nut 27 engaging the outer threaded portion of the 110 stem 21, this stem having an upset end 28 to prevent the nut from being entirely removed.

but permitting to operate in clamping the last section together.

The nut 27 has at its outer end a radially projecting lug 29, the same being adapted to enter a slot 30 formed in the lower end of the key wrench 31 provided with a bore 32 to engage over the nut 27 and transverse slots 33 connect with the longitudinal slot 30 by which the wrench may be used not only to turn the nut in either direction to clamp or release the sections, but also as a means for exerting an effective pull, transmitted through the stem 21 to the slideable plug 20, at that time in a forward position 10 and release the last from a shoe, a stout cross bar 34 being fixed in the key wrench for that purpose.

From the foregoing it will be readily understood that when the nut 27 is relaxed the sections may move relatively to the limit of the slot 23 and are prevented from turning with respect to each other by the key 15.

In the modification shown in Figures 4 and 5 a flat metallic angle is employed, one of its members 35 being inserted in the forward section 10 and held by a rod 36 rigidly therein at a right angle to the surface 11.

The other member 37 of the angle is received in a recess 38 formed in the corresponding surface 12 of the rear section 14 and is freely slideable in the recess the ends of which limit its movement.

Formed longitudinally in the angle member 37 is a slot 39 receptive of a pin 40 engaging the forks 41 of a cylindrical connector 42, the same extending into an opening 43 bored at a right angle from the surface 12 into the rear portion 14 of the 40 last.

The connector is internally threaded at its outer end to receive a screw 44 passing downward through a sleeve 45 having a flange 46 set in the upper part of the last 45 to act in receiving the thrust of a collar 47 formed on the screw 44, above which is a head engageable in the key wrench opening 32 and having a radial projection 48 to engage the slots 30 and 33 of the wrench.

Obviously slackening the screw 44 will permit the last sections to shift relatively within the limits of the slot 37, or by tightening the screw the last sections may be rigidly held in operative position.

It is furthermore to be noted that the element 37 acts as a key to prevent turning of the parts one with respect to the other.

From the foregoing it will be seen that an unusually strong and simple last has been disclosed in which the sections are movable upon being released or clamped tight for operative purposes, and it is to be noted that all parts are so connected as to be inseparable and therefore not subject to misplacement and loss.

It is also worthy of attention that a single key wrench may be used with any number of the lasts in which duplicate clamping nuts are employed.

Although the foregoing is generally descriptive of the best known embodiments of the device it will be understood that the same is subject to minor changes, not involving invention and which are within the scope of the appended claims.

Having thus described my invention, what I claim as new and desire to secure by Letters Patent, is:

1. A last comprising forward and rear sections meeting in an oblique plane and being relatively movable in such plane, and means for clamping the sections when in operative position, said means preventing disassociation, said clamping means being adapted to receive a wrench also operative in raising the last from a shoe.

2. A last comprising forward and rear sections meeting in an oblique transverse plane from the top of the instep to the front of the heel, means to prevent relative turning movement of said sections, means limiting relative sliding movement in the plane of their meeting surfaces, means including a cylindrical slide movable in one of said sections for guiding the sections and means for clamping the sections when in operative position, said clamping means also preventing complete separation of the parts.

3. A last comprising forward and rear sections meeting in an oblique plane and being relatively movable in such plane, a clamp bolt in the forward section to extend outwardly beyond the heel section, a nut on said bolt to cause clamping engagement between said sections, and a lateral pin fixed in said nut, said nut adapted to receive a wrench having a part engageable with said pin whereby a pull may be exerted on the last.

4. A last comprising forward and rear sections meeting in an oblique plane and being relatively movable in such plane, a threaded bar movable in the forward section to extend through the rear section, said bar acting as a stop to limit the relative movement of said sections, an adjustable clamp nut engaged on said bar beyond the rear section, and means for confining said nut on said bar.

5. A sectional last having a front and rear element meeting on an oblique plane, the front element having an opening adjacently parallel with the meeting faces, a bolt having a head slideable in the mentioned opening, means to limit the movement of said bolt, the rear element having a bore to receive said bolt, a clamp nut on the outer portion of said bolt to draw the elements into tight relation, and means to retain the nut in engagement with the bolt, said nut being adapted to receive a wrench for actuating and for applying tractive force to said nut.

6. A sectional last having a front and rear element meeting on an oblique plane, a tubular member fixed in the front element below and in a plane parallel with the meeting surfaces, said members being slotted through a portion of its length, a plunger freely movable in said member, a rod fixed in said plunger to extend through the slot in the tubular member, said rear element having a bore through which said rod projects, a thrust receiving bushing fixed in the outer end of the bore, a nut threaded on the end of said rod to engage said bushing, means on the end of said rod to retain the nut thereon, said nut being engageable with a wrench, and means cooperative with said nut and wrench to exert pull on the last.
7. A last comprising forward and rear sections meeting in an oblique plane and being relatively movable in such plane, said rear section having a portion of its upper surface parallel therewith, a sleeve fixed in said parallel portion, said rear section having a bore in register with the sleeve, said forward section having an opening parallel to the meeting surfaces, a slotted tube fixed in the mentioned opening, a slide movable in said tube, a bolt fixed in said slide to extend through said bore and bushing, a nut threaded on said bolt to impinge on said bushing in clamping the sections, means to retain said nut on the bolt, said nut being engageable with a wrench, and means on said nut cooperative with the wrench for exerting a pull on the last to free it from a shoe. 35
- Signed at New York in the county of New York and State of New York this 19th day of March, A. D. 1927.

SABINO GUBITOSI.
